UNITED STATES PATENT OFFICE

JOHN P. KOLAR, OF ERIE, PENNSYLVANIA

TIE-PLATE

Application filed October 29, 1928. Serial No. 315,809.

The invention is directed to an improvement in tie plates. Tie plates are ordinarily formed with the edges beveled, the bevel flaring inwardly in an upward direction. As the tie plate wears down into the tie the width of the notch so worn is determined by the bottom edge of the tie which presents a comparatively sharp edge to the wall thus formed. In my invention I reverse this bevel so that as the tie plate wears it sinks into the notch formed by the wear and the bevel takes up the slack so that there is not only a taking up of wear but the entire beveled surface is presented to the shoulder formed by the notch worn into the tie. Features and details of the invention will appear from the specification and claim.

A preferred embodiment of the invention is illustrated in the accompanying drawings 20 as follows:—

Fig. 1 shows a perspective view of the tie plate.

Fig. 2 a plan view, partly in section, of a track showing an alternative arrangement of 25 the tie plates.

Fig. 3 a section on the line 3—3 in Fig. 2. 1 marks the rails and 2 the ties of the track. A tie plate 3 is provided with a continuous hooked rib 4 adapted to hook over one edge of 30 the rail flange. Preferably the undersurface of the hooked end of the rib has clearance from the upper surface of the flange permitting a slight movement of the rail up and down relatively to the hooked edge, this 35 yielding assisting in preventing the movement of the tie plate on the tie.

A rib 6 is arranged on the tie plate and engages the opposite edge of the rail flange from that of the rib 4. Spike openings 7 are 40 formed in the plate, the inner wall of each spike opening being flush with the inner surface of the shoulder 6. This prevents the driving of the spike in a manner that the inner surface of the spike will be in rubbing engagement with the edge of the rail, the inner wall of the opening 7 holding the spike 45 free from such rubbing engagement.

Spike bracing shoulders 8 extend upwardly 50 from the plate, the inner face of these shoulders being flush with the other walls of the

opening 7. This extends up and braces the spike holding it with relation to the edge of the flange.

In Fig. 3 I show the spike 9 in place. The rib side of the plate is provided with spike 55 openings 10. These openings are more nearly adjacent to the edge of the plate than to the rib. This gives a greater leverage against a tendency to tip the plate under side strain at curves. A spike 11 is shown in the opening 10. By making the spike openings 10 spaced from the rib and the spike openings at the shoulder adjacent to the rail the plates when reversed bring the openings over portions of the tie free from previous spike 60 perforations. The edges of the plate are beveled at 12. As the plate wears into the tie these beveled edges engage the tie and prevent the side slipping of the plate. The bevel flaring upwardly outwardly as it does tends to 65 tighten the rail edgewise as it wears into the tie and presents the entire beveled surface to the engaging wall thus formed in the tie.

What I claim as new is:—

A tie plate having a rail seat on its upper 75 surface, said tie plate having the initial seating surface on its bottom in a single plane covering the major portion of the bottom and having its edges beveled outwardly in an upward direction and less than 45° from the 80 perpendicular, said tie plate having spike-receiving openings at opposite sides of the rail seat.

In testimony whereof I have hereunto set 85 my hand.

JOHN P. KOLAR.
